MAGAZINE FOR BINDER AND/OR WRAPPER
LEAVES

Martinus Verbakel, Eindhoven, Netherlands, assignor to N. V. Vereenigde Tabaksindustrieen Mignot & De Block, Eindhoven, Netherlands

Application January 4, 1951, Serial No. 204,299
In the Netherlands January 9, 1950

3 Claims. (Cl. 131—105)

1

The invention relates to a device of the kind, described in the copending U. S. patent application No. 141,371, filed January 31, 1950, comprising a magazine for a pile of preformed binder or/and wrapper leaves for cigars, cigarillos or bunches thereof, said magazine having bottom members and members for the lateral confinement of said pile permitting the leaves to be placed one upon the other cross-wise in a plurality of predetermined directions, and a rotatably mounted vertical driving shaft adapted to carry said magazine upon its upper end and to periodically rotate or to oscillate it through a predetermined angle.

Such a magazine must be periodically refilled. To this end binder or/and wrapper leaves may be piled up cross-wise in a separate apparatus and the thus obtained pile may be taken out of the piling apparatus and inserted into the magazine of the machine for making the cigarillos, cigars or the bunches therefor. In practice this method of refilling the magazine appears to raise difficulties.

The invention has for its object to avoid these difficulties. It consists in that means for the detachable interengagement of the magazine and the shaft are provided, which means permit the magazine to be engaged by and to be disengaged from the shaft, respectively and prevent said magazine, when so engaged, rotating relative to said shaft. The invention thus enables the magazine to be taken out of the bunch or cigar making machine and placed in the refilling apparatus. The magazine having been refilled is adapted to be inserted again in the bunch or cigar making machine. Due to this fact the time, during which the machine has to stop for replenishing the stock of tobacco leaves, is considerably reduced.

According to the invention the upper end of the driving shaft may be provided with a non-circular, e. g. rectangular, flange and the lower surface of the magazine may have guide-elements, which are adapted to engage the flange of the driving shaft and constitute a guiding channel which is open at at least one of its ends, so that the guiding-channel is adapted to receive said flange when the magazine is brought into engagement with the driving shaft.

The magazine may have a separate vertically movable bottom plate, which is connected to an axially reciprocating vertical rod. The means for the interconnection of said rod and said bottom plate may consist of a flange provided at the upper end of said rod and of guide-members

2

mounted on the lower surface of said bottom plate and adapted to engage said flange. On one side of the magazine there is provided a slot or aperture which permits the horizontal disengagement of the magazine both from the vertically movable bottom plate as well as from the rod and driving shaft.

In order that the magazine may be held, when engaged by the driving-shaft, in the exact working position with respect to said shaft, locking means may be provided.

For the elucidation reference is made to the accompanying drawing which illustrates by way of example a device comprising a magazine according to the invention. In the drawing:

Fig. 1 is a horizontal sectional view of the magazine,

Fig. 2 is a view of the lower surface thereof,

Fig. 3 is partly an elevational and partly a sectional view of line III—III in Fig. 1, and

Fig. 4 is a sectional view on line IV—IV in Fig. 2, in which, however, the bottom plate is in its highest position.

The device according to the drawing comprises a magazine, which is provided with a horizontal bottom plate 1 and sidewalls 2 defining a space having the shape of a cross the corners of which are bevelled. The magazine is open at its upper end and is adapted to contain a pile of preformed binder or/and wrapper leaves, which are placed cross-wise one upon the other. The lower surface of the bottom plate 1 is provided with two parallel guide-elements 3 having a L-shaped cross section. The space between these guide-elements is bounded at one end of said elements by an abutment 4, which is also secured to the lower surface of plate 1. The other end of said space is open. In this space a rectangular flange 5 is inserted, said flange being secured to or forming an integral piece of the upper end of a hollow shaft 6. The flange 5 is slidably fitted in the space between the guide-elements 3. When the flange 5 abuts against the abutment 4, the axis of shaft 6 is in alignment with the axis of the magazine 1, 2. In this working position of the magazine the flange 5 is held by a locking device attached to the abutment 4 and consisting of a blade spring provided with a protruding head 7 which engages a hole or recess 8 made in the flange 5. The shaft 6 thus carries the magazine, which is moved together with said shaft, when the latter is rotated or oscillated. The magazine is adapted to be removed from said shaft in horizontal direction.

55 Mounted in the magazine 1, 2 is an individual

bottom plate 9, which is attached to the upper end of an axially reciprocating vertical rod 10. This bottom plate is adapted to bring the pile of tobacco leaves in a position in which the uppermost leaf of the pile can be removed by a leaf-holder and taken to another place in the bunch or cigar making machine. The plate 9 is provided with guide-elements 11 having L-shaped cross sections and engaging a flange or disc 12 which is mounted at the upper end of rod 10. In the plate 9 a slot 13 is made, said slot permitting the rod 10 to pass when the magazine is horizontally moved relative to the shaft 6. In the lower end of one of the side-walls 2, viz. the sidewall facing the open end of slot 13 and the space between the guide-elements 9, an aperture 14 is made, so as to permit the flange 12 and the rod 10 to pass. When the bottom plate 9 is in its lowest position, the magazine and plate 9 are allowed to be removed from the driving shaft 6 and the rod 10 in horizontal direction or brought into engagement with said shaft and said rod. Consequently, the entire magazine is adapted to be removed from the bunch or cigar making machine and placed into a refilling apparatus for replenishing the stock of binder or/and wrapper leaves.

What I claim is:

1. A device comprising, in combination, a magazine for holding a pile of tobacco leaves for cigars, cigarillos and the like, said magazine having side walls for laterally confining said pile with the leaves in superposed cross-wise relationship in a plurality of predetermined directions, a rotatably-mounted vertical driving shaft adapted to carry said magazine at its upper end and periodically to rotate the magazine through a predetermined angle, and means for detachably engaging said magazine and said shaft, said means comprising a flange provided on the upper end of said driving shaft and guide elements provided at the lower ends of said side walls, said guide elements detachably engaging the flange on the driving shaft and defining a guiding channel, said channel being open at one of its ends for permitting disengagement of said shaft from said magazine in a horizontal direction.

2. A device comprising, in combination, a magazine for holding a pile of tobacco leaves for cigars, cigarillos and the like, said magazine having side walls for laterally confining said pile with the leaves in superposed cross-wise relationship in a plurality of predetermined directions, a rotatably-mounted vertical driving shaft adapted to carry said magazine at its upper end and periodically to rotate the magazine through

a predetermined angle, and means for detachably engaging said magazine and said shaft, said means permitting the magazine to be engaged by and to be disengaged from the shaft, respectively, and preventing said magazine when so engaged from being rotated relative to said shaft, a vertically movable bottom plate provided in the magazine, an axially reciprocable vertical rod adapted to be connected to said bottom plate, a flange provided at the upper end of said rod, and guide members mounted on the lower surface of said bottom plate and engaged with said flange, and there being an aperture in one of said side walls of said magazine, said aperture permitting the magazine and the vertically movable bottom plate to be engaged by and to be disengaged from the driving shaft and the rod, respectively, in a horizontal direction.

3. A device comprising, in combination, a magazine for holding a pile of tobacco leaves for cigars, cigarillos and the like, said magazine having side walls for laterally confining said pile with the leaves in superposed cross-wise relationship in a plurality of predetermined directions, a rotatably mounted vertical driving shaft adapted to carry said magazine at its upper end, a flange provided on the upper end of said driving shaft, guide elements provided at the lower ends of said side walls, said guide elements detachably engaging the flange on the driving shaft and defining a guiding channel, said channel being open at one of its ends for permitting disengagement of said shaft from said magazine in a horizontal direction, a vertically movable bottom plate provided in the magazine, an axially reciprocable vertical rod adapted to be connected to said bottom plate, a flange provided at the upper end of said rod, and guide members mounted on the lower surface of said bottom plate and engaged with said flange, and there being an aperture in one of said side walls of said magazine, said aperture permitting the magazine and the vertically movable bottom plate to be engaged by and to be disengaged from the driving shaft and the rod, respectively, in a horizontal direction.
